UNITED STATES PATENT OFFICE.

JULIUS LARSON, OF NEW HAVEN, CONNECTICUT, ASSIGNOR OF ONE-HALF TO BICTOR SWANSON, OF NEW HAVEN, CONNECTICUT.

DRAFTING INSTRUMENT.

1,299,964.

Specification of Letters Patent.

Patented Apr. 8, 1919.

Application filed December 12, 1918. Serial No. 266,417.

To all whom it may concern:

Be it known that I, JULIUS LARSON, a subject of the King of Sweden, residing at New Haven, in the county of New Haven and 5 State of Connecticut, have invented a new and useful Improvement in Drafting Instruments; and I do hereby declare the following, when taken in connection with the accompanying drawings and the characters 10 of reference marked thereon, to be a full, clear, and exact description of the same, and which said drawings constitute part of this application, and represent, in—

Figure 1 a side view of a drafting instrument constructed in accordance with my invention.

Fig. 2 an underside view of the same.

Fig. 3 a broken sectional view showing the connection between the ends of the legs 20 and the blocks.

This invention relates to an improvement in drafting instruments and particularly to a device used in drawing semi-ovals, the object of the invention being to provide an 25 adjustable device with which ovals or semi-ovals of various major and minor axes may be perfectly transcribed; and the invention consists in the construction hereinafter described and particularly recited in the 30 claims.

In carrying out my invention I employ two legs 5 and 6 hinged together at their upper ends in the manner of a draftsman's compass. Beyond the pivot point 7 the 35 legs are connected by a ring-like spring the tendency of which is to expand the outer ends of the legs which are adapted to be drawn together by means of a nut 9 threaded upon a screw stem 10 which passes 40 through a stop eye 11 on one of the legs as 6 and is pivotally connected with the other leg. The ends of the legs 5 and 6 are respectively pivoted to blocks 12 and 13. Mounted in the block 13 is a horizontal guide bar 45 14 which extends through a clearance hole formed for it in the block 12 which is free to ride back and forth upon the guide-bar 14. Rigidly secured to the block 12 by a screw 15 is a band 16 of flexible spring 50 metal, the other end 17 of which passes between the outer wall of the block 13 and a

clamping plate 18 which plate is adapted to be clamped against the end of the band by means of a thumb screw 19 entering the block 13. Preferably and as herein shown, 55 a spring finger 20 will be secured to the block 12 by the screw 15, this finger bearing against the inner face of the band 16 and a similar spring finger 21 will be secured to the outer face of the block 13 and so as to 60 expand against the inner face of the adjustable end of the band, the tendency of these spring fingers being to force the band outward. Preferably and as herein shown pins 22 and 23 will be secured to the blocks 65 12 and 13, and so that their points project slightly below the lower faces of the blocks to locate the blocks on a sheet of drawing paper or the material on which the oval is to be made. To draw a semi-oval, the legs 5 and 6 will be adjusted according to the major axis of the oval. The band 16 will then be adjusted according to the minor axis of the oval, and when adjusted, will be clamped to the block 13 by the screw 19. 70 The outer edge of band thus forms half of an oval and the band forms a surface against which a pencil may rest in scribing the semi-oval. The device is then reversed 75 in position, the points of the pins 22 and 23 80 being inserted in the holes previously formed by them, and the other side of the oval may then be drawn. By employing the spring fingers 20 and 21, a comparatively light band may be employed as the spring fingers 85 tend to reinforce the band at the ends and give the band the proper curvature.

I claim:

1. A drafting instrument comprising a 90 pair of legs pivoted together, a spring normally tending to expand the outer ends of the legs, means for drawing the legs together, blocks secured to the ends of the legs, a band rigidly secured to one of the blocks and adjustably secured to the other block, 95 and spring fingers bearing against the inner faces of the band at opposite ends.

2. A drafting instrument comprising a 100 pair of legs hinged together, a spring connected with the said legs and tending to separate the ends of the same, means for drawing the legs together, a block pivotally con-

nected with each leg, a rod fixed to one block and extending through the other block, pins secured to said blocks and projecting below the lower faces thereof, and a flexible band 5 fixed to one block and adjustably connected with the other block.

In testimony whereof, I have signed this

specification in the presence of two subscribing witnesses.

JULIUS LARSON.

Witnesses:

JOHN E. SVENSSON,
CORNELIA SVENSON.
